United States Patent Office

Des. 210,479

Patented Mar. 12, 1968

210,479

PLATE OR SIMILAR ARTICLE

Ottorino N. Mercadante, Corning, N.Y., assignor to Corning Glass Works, Corning, N.Y., a corporation of New York

Filed Oct. 2, 1967, Ser. No. 8,804

Term of patent 14 years

(Cl. D44—15)

The figure is a top plan view of a plate of conventional configuration showing my new design.

I claim:

The ornamental design for a plate or similar article, as shown and described.
